UNITED STATES PATENT OFFICE.

ROBERT E. DAVIES, OF ST. JOSEPH, MISSOURI.

CAR-STOP.

No. 925,875.

Specification of Letters Patent. Patented June 22, 1909.

Application filed April 2, 1909. Serial No. 487,394.

To all whom it may concern:

Be it known that I, ROBERT E. DAVIES, a citizen of the United States, residing at St. Joseph, in the county of Buchanan and State of Missouri, have invented new and useful Improvements in Car-Stops, of which the following is a specification.

My present invention relates to improvements in car stops of the class that are adapted to be applied to the rail and to serve as an abutment for a car wheel in order to limit or prevent movement of a car when upon a siding or the like, and it has for its object primarily to provide a simple and inexpensive device of this class that is adjustable so that it may accommodate itself properly to rails of various sizes and which when in use may be readily manipulated either to adjust it according to the size of the rail or to lock or unlock it, the device when in locked position uniformly distributing the force of resistance when the pressure is brought against it by the car wheel, and the device moreover is so constructed that it 25 clears the flange of the wheel when locked so as to prevent fracture of the flange, and when unlocked it will be thrown clear of the rail by the car wheel should the device be inadvertently left upon the rail, derailment 30 being thereby prevented.

To these and other ends, the invention consists in certain improvements, and combinations and arrangements of parts, all as will be hereinafter more fully described, the 35 novel features being pointed out particularly in the claims at the end of the specification.

In the accompanying drawing: Figure 1 is a perspective view of an adjustable car stop constructed in accordance with my present invention, the same being shown applied to a railroad rail; Fig. 2 represents a vertical section through the rail and the stop fitted thereon, the locking lever being shown in partially locked position; Fig. 3 represents a side elevation of the device, the locking lever thereon being shown in the same position it occupies in Fig. 2; and Fig. 4 is a perspective view of the locking lever.

Similar parts are designated by the same reference characters in the several views.

Adjustable car stops constructed in accordance with the present invention are capable of use in connection with rails of various sizes and shapes, although in the present instance, I have shown them adapted for use in connection with the ordinary

T-rail such as used generally on railroads. The stop consists of a block 1 which may be composed of cast or wrought iron and one side of the block adjacent to its lower edge is recessed so as to enable the block to fit upon the ball 2 of the rail and also to engage beneath the ball of the rail whereby the block may be locked down on the top of the rail. This recess in the present instance is so shaped as to form a horizontal wall 3 which rests flatwise on the upper side of the ball of the rail and the lower wall 4 of the recess is preferably inclined so as to fit and engage the under side of the ball of the rail, the inner side of the block below the inclined wall 4 extending vertically as at 5 so as to rest against the web of the rail and thereby prevent turning or tilting of the block. The upper portion of the block is 15 preferably of such a width that its inside face is contained within the width of the ball of the rail as shown in Fig. 2, and consequently the flange upon the car wheel will not be struck by the block and in this manner fracture of the wheel flange is prevented.

A bolt 6 extends horizontally through the upper portion of the block and is freely turnable therein, this bolt having a capstan 85 head 7 serving as a shoulder at the outer side of the block, and in order to facilitate the adjustment of the device especially without the use of a wrench or other tool, this head is provided with a handle 8 which may 90 slide through the head and enable the operator to easily adjust the bolt. The locking lever 9 is turnable about the bolt 6 as an axis and in order to enable the lever to be adjusted with respect to the block so that the device may be fitted to rails of different sizes, the bolt 6 is formed with a thread 10, a left hand thread being shown in the present instance and this threaded end of the bolt co-operates with the lever 9. This 100 lever 9 is composed of a handle portion which may be of any appropriate length that will enable the device to be locked and unlocked with facility, and it also has a cam portion 11 which extends in approximately right angular relation to the handle whereby this cam portion may be in locking engagement with the rail while the handle portion of the lever is pressed down into parallelism or close proximity to the rail 110 and thereby avoids the formation of an obstruction on the track. This cam portion is

provided with a slope or incline 12 at its inner side and at one corner, this slope or incline coöoperating with the inner side of the ball of the rail when the handle of the 5 lever is depressed and thereby causing a locking action of the lever and block upon the rail that is interposed between them. In the present instance, the left hand thread of the bolt 6 acts to assist the cam 12 in 10 locking the block upon the rail while the lever is being turned into locked position. When the stop is in locked position upon the rail, the inner face of the block is offset outwardly from the inner face of the ball of 15 the rail, and consequently, the tread only of the car wheel will strike the stop, the flange of the wheel passing clear of the block at its inner side and thereby avoiding injury to the wheel flange. Should it happen that the stop is unlocked but the car 20 wheel strikes it before it has been removed from the rail, the block would be engaged by the wheel and would be thereby thrown clear of the rail.

25 Obviously, the invention is capable of use in all instances where it is desirable or necessary to limit or prevent movement of a car or cars, it being especially useful on coal chutes, elevators, mines and in similar 30 instances for the purpose of stopping a car either loaded or empty at a given point after the car has been set in motion for instance by a pinch bar or by hand power.

I claim as my invention:

- 35 1. A car stop comprising a pair of pivotally connected members, one adapted to engage a side of a rail and the other turnable and having means for producing a wedging action against the opposite side of a rail and 40 to thereby lock the stop thereto.
2. A car stop comprising a block adapted to engage one side of a rail, and a lever pivotally connected to said block on an axis transverse to the rail and arranged to engage 45 the opposite side of the rail to clamp the block thereto.

3. A car stop comprising a block shaped to receive the ball of the rail, and a lever pivoted to said block and having a cam portion to have a wedging engagement with 50 the opposite side of the rail to thereby lock said block thereto.

4. A car stop comprising a block recessed at one side to receive the ball of a rail, and a lever turnable about an axis transverse to 55 the rail and comprising a handle portion, and a cam portion depending in angular relation thereto and shaped to coöperate with the ball of the rail at one side.

5. An adjustable car stop comprising a 60 block recessed at one side to receive the ball of a rail, a lever having a cam portion at its inner side to coöperate with that side of the ball of the rail opposite to the side received by said block, and a bolt serving as an adjustable pivot connecting the block and lever whereby the stop may be adjusted to rails of 65 different sizes.

6. An adjustable car stop comprising a block shaped to receive the ball of a rail, a lever having a cam portion to engage the rail, and a bolt turnable in the block and threaded into the lever and serving as an adjustable pivot to adapt the stop to rails of 70 different sizes.

7. An adjustable car stop comprising a block shaped to receive the ball of a rail, a lever having a portion to directly engage the ball of the rail to thereby lock the block thereto, and a bolt forming a pivot for said 80 lever, said bolt being threaded and having its pitch so arranged that turning of the lever will cause the lever to approach the block.

In testimony whereof I have hereunto set 85 my hand in presence of two subscribing witnesses.

ROBERT E. DAVIES.
